JAMES G. MACLAREN, OF MAMARONECK, NEW YORK.

ELECTRICALLY-CONTROLLED DUMB-WAITER.

Application filed July 5, 1924. Serial No. 724,544.

This invention relates generally to improvements in dumb-waiters of the electrically controlled type.

In the operation of electrically controlled dumb-waiters as heretofore known and used considerable difficulty has been found in preventing the car from responding to the control exercised by a closed circuit controller at a distant station and leaving the station 10 at which it has come to rest before the attendant has had an opportunity to open the hatchway door. It is a common practice in the art to provide a safety switch mechanism to prevent the operation of the car while any 15 door is open but no provision has heretofore been made to prevent the starting of the car immediately after it has come to rest and before the hatchway door has been opened.

The present invention includes means providing for the elapse of a predetermined interval of time following the stopping of the car before it can be again started by the closing of a control circuit at a distant point. This delay or pause of the car at a station is 25 of sufficient duration to enable the attendant at the floor station to open the hatchway door and therefore remove articles from or place them on the car without such interruption as would be occasioned by the removal of the 30 car from the station in response to the control exercised by an operator at a distant station.

An embodiment of means for producing the functions referred to consists of a slow-acting circuit controller in the push-button 35 motor-starting circuit which is operated by current flowing through either the starting circuit or through the main-line motor switch circuit. The circuit controller is arranged to interrupt the starting circuit as the main line 40 circuit is closed and to maintain the interruption in the starting circuit until the main line circuit has been opened and the car has come to rest. Upon cessation of the flow of current in the main line circuit the controller 45 is arranged to provide a retarded or delayed circuit closing action so that the starting circuit cannot be utilized until after the lapse of a period of time following the stopping of the car at a station.

50 In the drawings, in which a preferred form of the invention has been selected for illustration,

Figure 1 is a view in diagrammatic form of an embodiment of the invention and the 55 wiring arrangement employed therewith.

Figure 2 is a sectional view on an enlarged scale of a magnetically operated circuit controller forming part of the invention.

Figure 3 is a view in side elevation of the circuit controlling device shown in Figure 2. 60

Referring to the drawings for a more detailed description of the invention, at 5 and 6 are shown the terminals of a current feed or supply circuit from which current may be supplied to either the up coil 7 or to the down coil 8 of a main switch operating magnet or relay 9.

At 10 and 11 is represented a set of up and down push buttons by which a starting circuit may be closed to actuate the corresponding up or down coils 7 or 8 of the main relay 9. The starting circuit for the up coil and push button may be traced as follows: feed wire terminals 5, conductor 12, conductor 13, contact 14, bridge contact member 15, contact 16, conductor 17, branch conductor 18, push button contact 10, conductor 20, up coil 7 of relay 9, and conductor 21 including coil 22 back to terminal 6. A corresponding starting circuit for the down coil and push button is as follows: terminal 5, conductors 12-13-17 as before, down push button contact 11, conductor 24, down coil 8 of relay 9, and common return conductor 21 to feed terminal 6. 85

A supplemental control of the starting circuits referred to is provided by the bridge contact 15 in its relation to a gap 25 between the contact terminals of the conductors 13 and 17. To effect this the coil or solenoid 22 is provided with a plunger armature 26 carrying at its lower end the bridge contact member 15 and at its upper extremity terminating in a piston 27 adapted to rise readily in the cylinder 28 but to move slowly downward therein. By this construction it will be seen that the flow of current which energizes either one of the relay coils 7 or 8 at the same time energizes coil 22 and lifts the contact member 15 out of bridging relation 90 with the contacts 14 and 16, thereby producing a gap in the starting circuit. 100

It will be seen that the relay 9 is of the holding or stick type in that the energization of either coil 7 or 8 lifts a corresponding 105 armature 29 or 30 into engagement with sets of contacts 31 or 32 in a branch conductor 33 which serves to shunt out the push button circuit closers and maintain the coil circuit closed until interrupted by a suitable car 110

stopping device, not shown. The armatures 29 and 30 are conveniently connected to a reversing switch, not shown, for controlling the duration of rotation of the motor. It will be seen that once the coil 22 has been energized the contact member 15 is lifted and a starting circuit cannot again be closed until the flow of current through the main control switch relay has ceased.

10 It has been stated that the piston 27 moves upwardly readily but moves downwardly slowly. To achieve this the piston is provided with an inverted leather cup-shaped disk or member 34 and the cylinder 28 is 15 provided with an air inlet port 35 controlled by an adjustable needle valve screw 36 by which the time interval required for the descent of the piston and the closing of the gap 25 in the starting circuit can be adjusted as 20 desired.

It will be seen that with the construction described a time interval can be provided following the time when a car stops at a station and before the motor can again be started to afford an opportunity for the attendant to open the hatchway door.

What is claimed is:—

1. In electrical controlling means for dumb-waiters, a starting circuit, a main car 30 operating circuit, and a solenoid including a piston having restricted movement in one direction and responsive to the condition of the car operating circuit and controlling the car starting circuit for preventing the actuation 35 of the car moving means for a predetermined

interval of time following the stopping of the car at a station.

2. In electrical controlling means for dumb-waiters, a starting circuit, a main car control circuit, a circuit controller arranged to open or close a gap in the starting circuit, said circuit controller arranged to be set into operation to open the gap when current flows through the main circuit, said controller operating to automatically close the gap in the starting circuit upon cessation of the flow of current in the main circuit, and means for retarding the gap-closing action of the controller to provide a time interval between the stopping of the controller to provide a time interval between the stopping of the car at a station and its subsequent starting.

3. In electrical controlling means for dumb-waiters, a starting circuit, a main car control circuit, a circuit controller arranged to open or close a gap in the starting circuit, said circuit controller being arranged to be set into operation to open the gap when current flows through the starting circuit and to be maintained in gap-opening condition by the flow of current in the main control circuit, said controller operating to automatically close the gap in the starting circuit upon cessation of the flow of current in the main circuit, and adjustable means for retarding the gap-closing operation of the controller to provide a time interval following the stopping of a car at a station before the car can be again started.

JAMES G. MACLAREN.
